(57) **CLAIM**

The ornamental design for a linen sheet and pillow sheet set, as shown and described.

DESCRIPTION

FIG. 1 is a front perspective view of a linen sheet and pillow sheet set;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged cross sectional view thereof, taken along line 8-8 in FIG. 6.

The broken lines represent the bounds of the claimed design, it being understood that the broken lines form no part of the claimed design.

1 Claim, 6 Drawing Sheets(56)
